UNITED STATES PATENT OFFICE.

WILLIAM F. HELMOND, OF HARTFORD, CONNECTICUT, ASSIGNOR TO UNDERWOOD
TYPEWRITER COMPANY, OF NEW YORK, N. Y., A CORPORATION OF DELAWARE.

TYPE-WRITING MACHINE.

1,148,167.

Specification of Letters Patent. Patented July 27, 1915.

Application filed December 9, 1912. Serial No. 735,611.

To all whom it may concern:

Be it known that I, WILLIAM F. HELMOND, a citizen of the United States, residing in Hartford, in the county of Hartford and 5 State of Connecticut, have invented certain new and useful Improvements in Type-Writing Machines, of which the following is a specification.

My invention relates to means for connecting and disconnecting the platen and line-space wheel in typewriting machines.

The primary object of my invention is to provide a simple and practical device of the character above indicated which will effect- 15 ually prevent slipping or relative rotation of the platen and line-space wheel while they are connected to rotate together.

The requirements for a practical clutch device between the platen and line-spacer 20 are exacting. In the first place, it is essential that there shall be no slipping whatever, which necessitates a clutch that is powerful and positive in action. At the same time it is important that the means to apply and 25 release the clutch shall operate with ease and without any tendency to throw the platen out of its adjusted position relative to the line-space wheel.

The present invention is designed to meet 30 the above requirements, and to provide a construction embodying various features of novelty and utility as will appear more fully hereinafter in connection with the detailed description.

An important feature of my invention is 35 found in the use of a plurality of gripping jaws or grips in the clutch, whereby the gripping action is multiplied and slipping effectually prevented. In the patent to Ney, 40 No. 979,991 of December 27, 1910, a split ring in the clutch is employed. In the present invention I use more than one gripping jaw, while at the same time a single cam is 45 required to release or expand the gripping jaws. The symmetrical arrangement of the gripping jaws on opposite sides of the axle also overcomes the usual tendency to rotate the line-space wheel through a slight angle when the clutch is being operated.

50 My invention also provides a toggle connection between the clutch jaws and the

operating levers, whereby a very powerful gripping action is secured.

A further feature of the invention resides in the use of a latch to automatically lock 55 the clutch-operating cam against accidental movement toward a released position. A lost motion connection between the cam and the thumb-piece for actuating the same permits the latch to be released during the 60 preliminary movement of said thumb-piece to release the clutch.

Other features and advantages will hereinafter appear.

In the accompanying drawings which 65 illustrate the principles of my invention, Figure 1 is a perspective view of a clutch device and associated parts. Fig. 2 is a part sectional elevation view of the same. Fig. 3 is a perspective view of the expandable clutch jaws or grips and operating means therefor. Fig. 4 is an enlarged detail view of parts shown in Fig. 3. Figs. 5 and 6 are elevation views showing the clutch in its released and applied positions respec- 70 tively. Figs. 7 and 8 are detail views of a latch in its released and locking positions respectively.

The usual cylindrical platen 1 is fixed to the axle 2 journaled in the ends of a platen 80 frame 3. A lever 4 is adapted to operate a slide 5 which carries a pawl 7 coöperating with the line-space wheel 6, the latter being held in operated position by the usual detent 8. The line-space wheel 6 is mounted 85 for rotation on the axle 2 to permit independent adjustment of the platen, but under normal working conditions is securely held against such rotation by my improved clutch, as will presently be described. Be- 90 tween the platen and the line-space wheel is a collar 9 adjustably secured to the shaft by a set screw.

The clutch comprises a clutch part 10 rigidly secured to or formed integral with 95 the wheel 6, and provided with an annular flange 11 forming a drum. Within the flange 11 is a disk 12 fixed to the axle and having a hub extension 13 forming a bearing for the part 10 and wheel 6. Expansion 100 clutch members in the form of jaws or grips 14 are adapted to be sprung into frictional

engagement with the inner periphery of the flange 11. The grips 14 are preferably of annular structure, each being a segment of a ring, and are made of spring steel and are curved to conform to the bearing surface of the drum throughout their length except at their ends which are bent inward at an angle to said bearing surface. The two grips 14 thus form an expansion ring having a plurality of separate expansible segments each adapted to be sprung into lengthwise engagement with the flange 11 to grip the same.

A block 15 is rigidly secured to the disk 12 by rivets 16 or other suitable means, and is formed with bearing notches 17 for the ends of the grips 14. For the purpose of adjusting the grips 14, the block 15 is split and threaded to receive an adjusting screw 18, the screw-opening being countersunk or tapered so that the block 15 may be expanded by setting up the screw. This provides for an accurate and fine adjustment of the grips 14.

The clutch grips 14 are expanded into clutching position by a pair of levers 20 fulcrumed on a floating fulcrum pin 21 free to move laterally and equalize the pressure on the grips 14. The levers are provided with bearing recesses for the fulcrum pin. The ends of the grips 14 engage in notches 22 formed in the levers 20. It will be observed that the direction of each bearing notch 22 from the fulcrum pin is substantially at right angles to the general direction of the lever, so that the levers 20 are in effect bell crank levers, and when the levers 20 are spread, the bearing points 22 are carried upward. By reference to Fig. 5, it will be seen that the upper end of each grip 14 is bent away from the flange 11 at a point 23 which is so located relatively to the fulcrum 21 and bearing point 22 that the latter is slightly below the line joining the point 23 with the fulcrum 21. There is thus formed a toggle comprising the horizontal arm of the lever 20 and the deflected portion of the grip 14.

It will now be apparent that an outward pressure on the lever 20 will cause a multiplied pressure in an upward direction at the bearing point 22, which, owing to the toggle arrangement, will result in a very powerful outward pressure at the point 23. This pressure applied in an endwise direction to the clutch grip 14 causes it to powerfully grip the flange 11. As a very small movement of the grip 14 is sufficient to carry it from released to gripping position, the power applied to the levers 20 is multiplied to an extent to secure a very effective and reliable clutching action. By setting up the screw 18 the block 15 is spread so that the points at which the grips abut said block are moved outward and reduce the distance from

said points to the points of contact with the levers 20, thus increasing the gripping power of the grips. A cover plate 35 is secured to the flange 11 and prevents displacement of the clutch jaws 14 and levers 20.

I am aware that it is not new to employ a split ring in a clutch between the line-space wheel and platen of a writing machine, as shown for example in said patent to Ney, 979,991, but the form of expansion clutch member 14 and operating means therefor as disclosed in the present application I believe to be new, effective and practical.

Another important feature of the present invention resides in the use of a plurality of expansion members combined in a single clutch and controlled and operated by a single operating device as hereinafter described. I have found that a clutch member in the form of a half ring, as the grip 14, is fully as effective as the usual split ring extending nearly around the clutch, and when formed and applied as above disclosed, is much more effective. It also permits the use of two expansion grips 14 in the same clutch and located in the same plane. This provides a symmetrical structure that permits the use of a single operating device which is simple and effective, and which automatically distributes the gripping pressure equally between the two grips. It will thus be seen that much more than a mere duplication of parts is involved.

The mechanism for operating the clutch will now be described. A thumb-wheel 25 is mounted on a metal sleeve or hub 26 fixed on the end of the platen axle 2. The hub 26 is formed with cylindrical openings parallel with the axle to receive rods 27, 28 and 29 slidably in said openings. A thumb-piece 30 is secured to the outer ends of the rods 27, 28. A clutch-operator 31 is mounted on the axle 2 between the clutch and the thumb-wheel 25, and is adapted to be moved longitudinally of the axle by means of the thumb-piece 30 and rods 27, 28. Each of said rods is formed with a reduced portion or neck 32 and a head 33 at the inner end of the rod. The right hand end of the operator 31 forms a hollow cylinder or barrel to receive the heads 33 which engage behind a flange 34 formed at the end of said operator. This arrangement permits a relative longitudinal movement of the operator 31 and the rods 27, 28, for a purpose which will presently be described. The inner end 36 of the operator 31 is tapered and when moved inward between the levers 20 acts as a cam or wedge to spread the levers and operate the clutch jaws as heretofore explained. The rod 29, which may be termed a locking rod, is connected to the operator 31 by means of a head 37 which engages behind the flange 34. It will be noted that

the space between the head 37 and the body of the rod is only sufficient to receive the flange 34, so that there is little or no lost motion between the rod and the operator 31.

- 5 A latch 38 is mounted on a pivot pin 39 in a slot 40 formed in the hub 26. The latch is adapted to engage behind the locking rod 29, and is moved to such position by a spring 41. The rod 28 is formed with a restricted portion or neck 42, which, when the thumb-piece 30 has been pushed inward to operate the clutch, permits the latch to move inward to locking position. From the neck 42 the rod is tapered outwardly to form a cam surface for lifting the latch.

15 The complete operation of the clutch mechanism may be briefly reviewed as follows: In Figs. 1, 2, 3, 5 and 7, the parts are shown in the position assumed when the thumb-piece 30 has been pulled outward to release the clutch and permit the platen to be rotated independently of the line-space wheel. To connect the line-space wheel and platen, the thumb-piece 30 is pushed inwardly. The initial movement carries the rods 27, 28, inwardly to take up the lost motion and brings the heads 33 up solidly against the operator 31. The continued inward movement of the thumb-piece carries 25 the cam 36 inward through an opening 35' in the plate 35. The cam 36 entering between the levers 20 forces them apart and operates the clutch as heretofore explained. The locking rod 29 is carried inward with 30 the operator 31 and passes beyond the latch 38 as the operator 31 completes its movement. The neck 42 is now opposite the latch and permits it to drop behind the locking rod, as shown in Figs. 4 and 8. The cam 36 35 is thus positively prevented from slipping back and locks the clutch in operated position. There is therefore no possibility of the clutch accidentally working loose and permitting slippage between the platen and 40 line-space wheel. To release the clutch the thumb-piece 30 is pulled outward. The lost motion connection permits the rod 28 to move outward and lift the latch 38 to free the locking rod 29 before the pull on the 45 thumb-piece is transmitted to the operator 31. The continued outward pull on the thumb-piece retracts the cam 36 and releases the clutch.

50 My invention comprises such modifications as come within the terms and scope of the appended claims.

Having thus described my invention, I claim:

- 55 1. In a typewriting machine, in combination, a platen, a loose line-space wheel, and a clutch mechanism for connecting said platen and line-space wheel comprising a drum, a split ring therein having deflected end portions, levers, a fulcrum pin for the levers, 60 said levers and deflected portions forming 65

toggles between the fulcrum pin and said ring, and means to operate the levers.

2. In a typewriting machine, the combination of a platen and axle, a line-space wheel loose on the axle, and clutch mechanism comprising a member secured to said wheel and formed with an internal circumferential bearing surface, a member fixed to the axle, gripping devices adapted to engage said bearing surface and bearing at one end against said member, and means between the other ends of said gripping devices to spread them into gripping engagement with said bearing surface.

3. In a typewriting machine, the combination with a roller platen and axle, of a line-space wheel loose on the axle, a drum secured to the said wheel, a disk within the drum and fixed to the axle, a bearing block carried by the disk, resilient grips curved to conform to the inner periphery of the drum and each having an end bearing against said block, and means between the opposite ends of the grips to spread them into engagement with the drum.

4. In a typewriting machine, the combination with a roller platen and axle, of a line-space wheel loose on the axle, a drum secured to said wheel, a bearing member within the drum and having a fixed connection with the axle, spring grips curved to conform to the inner periphery of the drum and having their ends bent inwardly, one end of each bearing against said bearing member, levers between the other ends of the grips, and means to operate the levers.

5. In a typewriting machine, the combination of a roller platen and axle, a line-space wheel loose on the axle, a drum secured to the wheel, expandable grips within the drum, bell crank levers to operate said grips and having arms straddling the said axle, a cam wedge mounted on the axle and movable longitudinally thereof to operate the levers, and means to actuate the cam wedge.

6. In a typewriting machine, the combination of a roller platen and axle, a line-space wheel loose on the axle, a clutch to connect the wheel and axle, a clutch-operating device mounted on the axle and slidable longitudinally thereof into position to clutch the wheel to the axle, a latch operable automatically into position to hold said device against retrograde movement from said position, and a releasing device operable to withdraw said latch to release the clutch-operating device, and then actuate the clutch-operating device to disconnect the platen and line-space wheel while the latch is held withdrawn.

7. In a typewriting machine, the combination of a roller platen and axle, a line-space wheel loose on the axle, a clutch for connecting the wheel and axle, a clutch-operating

device, an automatic lock for said device, and manual means to operate said device to release the wheel from the axle and operable to automatically release the lock prior to

5 said release of the wheel.

8. In a typewriting machine, the combination of a roller platen and axle, a line-space wheel loose on the axle, a clutch for connecting the wheel and axle, a clutch-operator 10 movable longitudinally of the axle, means to automatically lock said operator in operated position, a manual device to move said operator into and out of operated position, and means associated with the manual device to 15 automatically release the lock.

9. In a typewriting machine, the combination of a roller platen and axle, a line-space wheel loose on the axle, a clutch for connecting the wheel and axle, a clutch operator 20 movable longitudinally of the axle, means to automatically lock said operator in operated position, a manual device to actuate said operator and having a lost motion connection therewith, and means operated by said 25 manual device to release the locking means while the lost motion is being taken up in retracting the manual device.

10. In a typewriting machine, the combination of a roller platen and axle, a line-space 30 wheel loose on the axle, a clutch for connecting the wheel and axle, an operator mounted on the axle and movable longitudinally thereof to operate the clutch, a latch movable into position behind said operator to hold it in operated position, a manual releasing means having a lost motion 35 connection with said operator, and means associated with said manual means to retract the latch while the lost motion is being taken up.

11. In a typewriting machine, the combination of a roller platen and axle, a line-space wheel loose on the axle, a clutch for connecting the wheel and axle, a thumb-wheel 45 secured to the axle, a clutch-operator mounted on the axle between said thumb-wheel and clutch and movable longitudinally of the axle, a latch mounted in the thumb-wheel and operable to lock said operator in operated position, and manually operable 50 means extending through the thumb-wheel to operate the latch and clutch-operator.

12. In a typewriting machine, the combination of a roller platen and axle, a line-space 55 wheel loose on the axle, a clutch for connecting the wheel and axle, a thumb-wheel fixed to the axle, a clutch-operating cam mounted on the axle between the clutch and thumb-wheel and movable longitudinally 60 of the axle to operate the clutch, a locking rod connected to the cam, a latch pivoted in the thumb-wheel in position to engage behind said rod when the cam is moved to clutch-operating position, a thumb-piece, and rods connected thereto extending

through the thumb-wheel and having a lost motion connection with the said cam, one of said rods having a cam surface to operate the latch.

13. The combination with a platen axle, a platen fixed thereto and a loose line-space wheel, of clutch mechanism for connecting the platen and line-space wheel, an operator for said mechanism movable longitudinally of the platen axle, a locking device for said operator movable transversely of the axle into and out of position to hold the operator in operated position, a finger-piece to actuate said operator and having a lost motion connection therewith, and means operated by said finger-piece while the lost motion is being taken up to automatically release said locking device.

14. The combination with a platen and line-space wheel, of friction clutch mechanism to connect the platen and line-space wheel, said mechanism comprising a clutch part having a peripheral friction-holding surface, a pair of opposite clutch grips of annular structure curved to conform to the curvature of said surface and extending along said surface, and having their ends adjacent, said grips capable of being bowed by pressure thereon endwise thereof into lengthwise engagement with said surface to grip the same, a finger piece, and a single train of operating devices to spring said grips into frictional holding engagement with said surface and thereby lock the platen for rotation with the wheel, said train extending from said finger piece to one pair of adjacent ends of said grips, and the other ends thereof being supported against movement.

15. In a typewriting machine, the combination of a platen, a loose line-space wheel, a clutch connection comprising a device having a peripheral friction bearing surface, a split ring comprising a pair of ring segments curved to conform to the said surface and extending along opposite sides thereof, and having their ends adjacent, said segments capable of being sprung by pressure applied to the ends thereof into lateral engagement with the said surface to grip the same, and an operating device having means to apply endwise pressure to adjacent ends of said segments to spring them into gripping engagement with said surface, and thereby lock the line-space wheel to the platen, the other ends of said segments supported against movement.

16. The combination with a platen and a line-space wheel, of friction clutch mechanism to connect the platen and line-space wheel, said mechanism comprising a clutch part having a peripheral friction-holding surface, springy grips each of the form of a bow conforming to the curvature of said surface, and extending along said surface,

said grips capable of being sprung laterally into engagement with said surface to grip the same, means between adjacent ends of said grips to form an abutment for each grip to support the same against movement, and operating means to apply pressure only to the opposite ends of said grips in a direction lengthwise thereof to compress each grip between said abutment and said operating means and thereby cause it to spring laterally to grip said surface to lock the platen and line-space wheel together.

17. The combination with a platen and line-space wheel, of friction clutch mechanism to connect the platen and line-space wheel, said mechanism comprising a clutch part having a peripheral friction-holding surface, springy grips each in the form of a bow extending along the opposite sides of said surface and curved to conform to the curvature of said surface, means located between adjacent ends of said grips and forming an abutment for one end of each grip, operating means between the opposite ends of said grips for applying endwise pressure to said grips to spring them into lengthwise engagement with said surface to grip the same, and adjusting means to vary the position relatively to said operating means of the points of contact of the grips with the abutments and thereby regulate the pressure of the grips on said surface when operated by said operating means.

18. In a typewriting machine, the combination with a platen and a loose line-space wheel, of clutch mechanism to connect the platen to the line-space wheel, said mechanism comprising a drum, grips curved to conform to the inner periphery of the drum and extending therealong, said grips each capable of being sprung into gripping engagement with said drum, levers to actuate said grips, and a floating fulcrum for said levers, each of said levers operable to apply pressure to a grip and thereby spring it into gripping engagement with the drum, the re-acting pressure of each grip through its lever being in a direction opposing the re-acting pressure of the other grip through its lever, said floating fulcrum being held by said re-acting pressures in an equilibrated position in which the re-acting pressures counter-balance each other.

19. In a typewriting machine, the combination of a roller platen and axle, a line-space wheel loose on the axle, a friction clutch to connect said wheel and axle, a clutch-operating device, means to lock said device automatically in position with the wheel clutched to the axle, and a releasing device comprising means operable during the initial movement of the releasing device to release said lock, and operable during a further movement to then release the clutch.

20. In a typewriting machine, the combination of a roller platen and axle, a line-space wheel, a friction clutch to connect said wheel and axle, a clutch-operating device movable longitudinally of the axle, an automatic lock operative to hold said device in position with the wheel and axle clutched together, and means to hold the lock inoperative while the wheel is unclutched from the axle.

21. In a typewriting machine, the combination with a platen and a line-space wheel, of a friction clutch to connect the platen and wheel, said clutch comprising a clutch part having a peripheral friction surface, a plurality of cooperating springy friction grips of annular structure, curved to conform to said surface, and means to engage the ends of the grips to spring them endwise into engagement with said surface to grip the same, and a manual device to operate said grips.

22. The combination with a platen and a line-space wheel, of friction clutch mechanism to connect the platen and line-space wheel, said mechanism comprising a clutch part having a peripheral friction holding surface, springy grips of annular structure curved to conform to the curvature of said surface, and extending along said surface, said grips capable of being sprung into and out of lateral engagement with opposite faces of said surface to grip the same, means whereby said grips may be sprung by endwise pressure thereon into frictional holding engagement with said surface, and a single manually-operable device to control the operation of said grips, and thereby determine whether the platen and wheel shall be locked together or released from each other.

23. The combination with a rotary platen and a loose line-space wheel, of a friction clutch to connect the platen and wheel comprising a clutch part having a peripheral friction surface, a plurality of spring friction clutch grips of annular structure curved to conform to the curvature of said surface and adapted to be bowed or sprung into gripping engagement with different peripheral portions of said surface, actuating means to engage the ends of said clutch grips, to exert endwise pressure thereon to spring them into clutching engagement with said surface, a finger-piece movable in the direction of the platen axle for operating said actuating means, and a lock for said actuating means operated by said finger-piece while the latter is out of operative relation to said actuating means.

24. The combination with a rotary platen and a loose line-space wheel, of a friction clutch to connect the platen and wheel comprising a clutch part having a peripheral friction surface, a plurality of arc-shaped

friction bands lying along said surface, and an operating mechanism for applying pressure to each band in a direction to force the bands into gripping contact with said surface, the re-acting pressure of each band on the operating mechanism being in a direction to oppose that of the other band, said mechanism free to shift to a position in which said pressures are balanced, there-
5 by automatically equalizing the pressure of said bands on the said friction surface.

25. The combination with a platen axle, a platen fixed thereto and a loose line-space wheel, of clutch mechanism to connect the platen and line-space wheel, an operator for said mechanism movable longitudinally of the platen axle to operate the clutch mechanism and thereby lock the line-space wheel to the platen, and a locking device for said
15 operator movable transversely of the axle into and out of position to lock the operator mechanically in operated position with the line-space wheel locked to the platen.

26. The combination with a platen and a loose line-space wheel, of friction clutch mechanism to connect the platen and line-space wheel, said mechanism comprising a clutch part having a peripheral friction-holding surface, springy grips each comprising a gripping portion of annular structure curved to conform to the curvature of said surface, and extending along said surface, said grips settable to cause said gripping portions to be sprung into engagement
25 with said surface to grip the same, means forming an abutment or bearing for each grip to prevent movement of one end thereof, and means to operate the grips, the said gripping portion of each grip extending between its abutment and said operating means, the latter operable to force said grips by endwise pressure thereon into gripping engagement with the said surface, and thereby lock the platen and line-space wheel together.
30

27. The combination with a platen and a line-space wheel, of friction clutch mechanism to connect the platen and line-space wheel, said mechanism comprising a clutch
35 part having a peripheral friction-holding surface, springy grips each of annular structure, curved to conform to the curvature of said surface and extending longitudinally along said surface, said grips capable of being sprung, by force applied to the ends thereof, into lateral engagement with said surface to grip the same, means to form a support for one end of each of said grips to prevent movement of said end, means operating
40 at the other end of each grip in a direction lengthwise thereof to place the grip under tension between its said support and operating means, and cause it to grip said surface to lock the platen and line-space wheel together, and a finger-piece having
45

means to release both of said grips at a single operation.

28. The combination with a platen and a line-space wheel, of friction clutch mechanism to connect the platen and line-space wheel, said mechanism comprising a clutch part having a peripheral friction-holding surface, springy grips each in the form of a bow conforming to the curvature of said surface and extending along said surface,
50 said grips capable of being sprung laterally into engagement with said surface to grip the same, means to form an abutment for one end of each of said grips to prevent movement of said end, and operating means
55 to apply pressure to the other end of each grip in a direction lengthwise thereof, to compress each grip between its abutment and operating means, and thereby cause it to spring laterally to grip said surface to lock the platen and line-space wheel together.
60

29. In a typewriting machine, the combination with a rotary platen and a line-space wheel, of a clutch for connecting the platen and line-space wheel, said clutch comprising means forming a peripheral bearing surface, grips extending along opposite sides of said surface, a bearing block against which adjacent ends of the grips abut, operating means to engage the opposite ends of said grips, and move them into frictional holding engagement with said surface, and means to adjust said bearing block to vary the position of the grips relatively to said operating means, and thereby regulate the frictional pressure of the grips on said bearing surface when said operating means is actuated.
65

30. The combination with a platen and a line-space wheel, of clutching mechanism for connecting the platen and said wheel comprising a drum having an internal peripheral bearing surface, a pair of grips extending along opposite sides of said bearing surface, and movable into and out of frictional holding contact with said surface, a split block carried by said drum against which adjacent ends of the grips bear, an operating device for moving the opposite ends of said grips into position to cause them to grip said surface, and an adjusting screw to adjustably expand said bearing block, and thereby change the position of the grips relatively to the operating device, to regulate the pressure with which said grips will engage said surface when moved to gripping position by said operating device.
70

31. In a typewriting machine, the combination with a platen and a loose line-space wheel, of a drum secured to said wheel and provided with an internal peripheral friction-holding surface, oppositely disposed separate segments or grips each movable independently of the other and extending along opposite sides of said surface within
75

the drum and curved to conform to the curvature of said surface, said grips each terminating in an end portion extending away from said surface, and an operating 5 device to engage between said ends and apply pressure thereto in directions to spring said ends toward the peripheral surface and at the same time apply endwise pressure to the said grips to force them into frictional 10 gripping engagement with said peripheral surface.

32. The combination with a platen and a line-space wheel, of clutch parts to connect the platen and line-space wheel, means forming 15 an abutment for one of said parts, and an adjusting device to engage said means and adjustable to adjust the position of said means, and thereby vary the holding power of the clutch.

20 33. The combination with a platen and a line-space wheel, of clutch mechanism connecting the platen and line-space wheel, said mechanism comprising clutch parts movable into and out of gripping engagement, means forming an abutment for one 25 of said parts, and a screw-threaded adjusting device having a portion to bear against said means, said adjusting device adjustable by means of its screw-threaded portion working 30 in a correspondingly threaded socket to vary the position of said abutment.

34. The combination with a platen and a line-space wheel, of friction clutch mechanism to connect the platen and line-space 35 wheel, said mechanism comprising a pair of clutch parts, a spacing means between adjacent ends of said clutch parts, said means comprising parts expandible or movable toward and from each other, and a screw-threaded device for adjusting said means, said device comprising a portion to enter between and expand or spread the said parts of said means, said adjusting device adjustable by means of its threaded portion working 40 in a threaded socket, to adjust said spacing means.

35. In a typewriting machine, the combination with a roller platen and axle, of a line-space wheel loose on the axle, a drum secured to said wheel, a disk within the drum and fixed to the axle, grips curved to conform to the inner periphery of the drum, a spacing block between adjacent ends of said 50 grips and against which an end of each grip abuts, means between the opposite ends of the grips to spread them into holding engagement with the drum, said block comprising parts expandible to vary the relative position of the bearing surfaces for the grips, and thereby vary the pressure of said grips against the drum, and an adjusting screw to effect 55 said expansion of the spacing block.

36. The combination with a platen and a line-space wheel, of a clutch for connecting the platen and line-space wheel, said clutch 60

comprising a grip, and means forming a frictional holding surface against which said grip may be moved, an operating device for moving the grip into frictional holding engagement with said surface, means forming 70 an adjustable abutment for said grip, and an adjusting screw to engage said means and adjustable to vary the position of the point of contact of the grip and said abutment relative to the operating means, to 75 thereby regulate the frictional holding power with which the grip engages the said surface, when actuated by said operating means.

37. In a typewriting machine, the combination with a rotary platen and a line-space wheel, of a clutch for connecting the platen and line-space wheel, said clutch comprising means forming a peripheral bearing surface, grips extending along opposite sides of said surface, a split bearing block against which adjacent ends of the grips abut, operating means to engage the opposite ends of said grips and move them into frictional holding engagement with said surface, and an adjusting screw threaded between the parts of said bearing block to adjustably spread the block to vary the position of the grips relatively to said operating means, and thereby regulate 85 the frictional pressure of the grips on said bearing surface when said operating means is actuated.

38. In a typewriting machine, the combination with a rotary platen and a line-space 100 wheel, of a clutch for connecting the platen and line-space wheel, said clutch comprising means forming a peripheral bearing surface, grips extending along opposite sides of said surface, a split bearing block against 105 which adjacent ends of the grips abut, operating means to engage the opposite ends of said grips and move them into frictional holding engagement with said surface, and an adjusting screw threaded between the 110 parts of said bearing block and adjustable to spread said parts to vary the position of the grips relatively to said operating means, and thereby regulate the frictional pressure of the grips on said bearing surface when 115 said operating means is actuated.

39. The combination with a platen and a line-space wheel, of clutching mechanism for connecting the platen and said wheel, said mechanism comprising a drum having a 120 peripheral bearing surface, a pair of grips extending along opposite sides of said bearing surface and movable into and out of frictional holding contact with said surface, a split block against which adjacent ends of the grips bear, an operating device for moving the opposite ends of said grips into position to cause them to grip said surface, and an adjusting screw, the opposing faces of said block having threaded sockets to re- 125 130

ceive said screw and in which the screw is adjustable to expand said bearing block and thereby change the position of the grips relative to the operating device to regulate the pressure with which said grips will engage said surface when moved to gripping position by said operating device.

40. In a clutch for releasably connecting a platen and line-space wheel, the combination of a split block, and an adjusting screw,

said block having threaded sockets or recesses in its opposing faces to receive said screw, the bearing surfaces of the said sockets and screw being relatively formed to permit the block to be expanded by adjusting the screw therein.
